Frederick A. Kell, 2373 Fair Acres Road,
St. Louis County, Mo.

Filed May 12, 1959, Ser. No. 55,884

Term of patent 14 years

(Cl. D80—11)

FIG. 1.

FIG. 2

FIG. 1 is a perspective view taken from the top of a combined cooler and display stand embodying my new design; and

FIG. 2 is an enlarged center vertical cross-sectional view thereof.

The dominant features of my design reside in the full line portions of the drawing.

I claim:

The ornamental design for a combined cooler and display stand, substantially as shown and described.
